REFRIGERATING APPARATUS

Don E. Dasher, Dayton, Ohio, assignor to General Motors Corporation, Dayton, Ohio, a corporation of Delaware

Application November 25, 1938, Serial No. 242,177

15 Claims. (Cl. 62—5)

This invention relates to refrigerating apparatus and more particularly to absorption refrigerating systems employing a liquid absorbent.

It is an object of my invention to provide a liquid absorbent refrigerating system not requiring a pressure equalizing gas or pumps which will provide substantially continuous refrigeration.

It is another object of my invention to provide a continuous multi-pressure liquid absorption system without valves in the refrigerant circuit.

It is another object of my invention to provide a twin liquid absorption system in which the weak liquor is fed from one portion of the system to another.

It is another object of my invention to provide a liquid absorption system in which the condenser is also used as an absorber.

It is another object of my invention to provide a liquid absorption system without valves in which the absorption of the refrigerant in the weak liquor takes place by counter-flow of the weak liquor and the evaporated refrigerant.

It is another object of my invention to provide in a liquid absorption system, a generating means provided with a counter-flow heating arrangement.

It is another object of my invention to provide an absorption system with a manually initia- 25 ble defrosting device which automatically returns the system to normal temperature at the completion of the defrosting.

It is still another object of my invention to provide a control for an absorption refrigerating system which is responsive individually to evaporator temperature and the temperature of the compartment cooled by the evaporator.

Further objects and advantages of the present invention will be apparent from the following description, reference being had to the accompanying drawings, wherein a preferred form of the present invention is clearly shown.

In the drawings:

Fig. 1 is a view partly diagrammatic and partly sectional of an entire twin type liquid absorption system embodying my invention;

Fig. 2 is a sectional view of the burner control, together with the burner taken along the line 2—2 of Fig. 3;

Fig. 3 is a sectional view of the burner control taken along the line 3—3 of Fig. 2; and

Fig. 4 is a sectional view of the temperature control valve.

Briefly, I have shown a twin type liquid ab-

sorption machine having a series type of evaporating means which is divided into two portions, each portion being connected to a condenser which, in turn, is connected to a generator. A 5 restrictor is provided between the two portions of the evaporating means and weak liquor conduits are provided for conducting weak liquor from each generator to the top of the condenser connected to the other generator. A restrictor is placed in these weak liquor conduits in order to control the flow of weak liquor from the one generator to the condenser connected to the other generator. A thermostat is provided for swinging the burner so as to supply heat to one of the generators at a time, and for changing the supply of heat at the proper time from one generator to another. A thermostatic valve is provided for controlling the flow of gas to the burner according to evaporator and compartment temperatures. This valve is provided with a semi-automatic defrosting device.

The system

Referring now particularly to Fig. 1, there is shown a primary evaporating means having a portion 20 and another portion 22 which are divided by a restrictor 24. These two evaporating portions 20 and 22 are in heat exchange relation with the containers 26 and 28 which, together with the refrigerant portions 20 and 22 and the restrictor 24, are surrounded by insulating means. These containers 26 and 28 are connected by drain conduits 30 and 32 to a secondary evaporating means 34 containing a volatile liquid. The secondary evaporating means 34 is located in the compartment 36 to be cooled. The secondary evaporating means 34 is provided with shelves upon which may be frozen water in ice trays. The secondary evaporating means 34 is partially filled with the volatile liquid and the volatile liquid within the secondary evaporating means evaporates because of the absorption of heat in the air of the compartment 36 and this vapor passes upwardly through one of the tubes or conduits 38 or 32 into one of the chambers 26 or 28 where it is condensed and returned to the secondary evaporator 34 by the same path.

The primary evaporating means 22 is connected by the conduit 38 to a heat exchange portion 40 which, in turn, is connected to a trap 42 located at the bottom of the condenser 44. The top of the condenser 44 is also provided with a chamber 46 which, in turn, is connected by the conduit 48 to the top of the reservoir portion 50 of the one generator. A drain 52 is also

provided connecting the trap 42 with the lower portion of the reservoir 50.

The reservoir 50 is provided with a connection to an interchanger 54 which has its other end connected to the bottom of the jacket surrounding the generator heating flue 56. The top of the jacket surrounding the generator heating flue 56 is connected by a conduit 58 with the upper portion of the reservoir 50. The bottom of the jacket surrounding the generator flue 56 is provided with connecting conduit 60 which connects to the outer jacket of the interchanger 54 having its other end connected by a conduit 62 to a restrictor 64 which, in turn, is connected by a conduit 66 with the container 146 provided above the second condenser 144.

This second portion of the system is substantially identical to the first portion of the system and its respective parts are provided with reference characters 100 higher than the reference characters applied to corresponding parts of the portion of the system already described.

A swinging Bunsen type burner 68 is provided for heating either of the generators and is so positioned during the heating of the one generator that it discharges its products of combustion into the generator heating flue 56. These gases heat the rich liquor within the jacket surrounding this flue and thence pass to an upwardly extending flue 70 which connects with the flue 72 extending through a reservoir portion 50, after which the products of combustion pass upwardly and escape through a chimney 74.

Operation

The arrows indicate the direction of flow of strong and weak liquor and ammonia when the generator 82 is being heated. In operation, when the heating of the one generator starts, it is substantially filled with rich liquor while the other generator is substantially empty. The portion in the jacket surrounding the generator heating flue 56 is heated the most and the refrigerant is driven out of the liquor by the heat and passes upwardly out of the rear end of the jacket into the conduit 58 which extends upwardly and discharges into the upper portion of the reservoir portion 50 above the liquid level. This refrigerant in vapor form thence passes upwardly through the conduit 48 to the container 46 and thence flows downwardly through the condenser 44.

This refrigerant condenses in the condenser 44 and drains into a liquid trap 42 from which liquid refrigerant flows upwardly through the conduit 40 which is in heat exchange relation with the conduit 140, and thence the liquid refrigerant flows through the conduit 38 to the primary evaporating portion 22. The liquid refrigerant, however, does not evaporate until it passes through the restrictor 24 and reaches the other evaporating portion 20 where it evaporates under reduced pressure and condenses the volatile secondary liquid in the container 26. The vaporized volatile secondary liquid is thus condensed and returned to the evaporating means in this manner. The primary evaporating portion 22 supplies little or no heat to the volatile secondary liquid because the container 26 contains only vapor and the heating of this vapor will prevent any substantial amount of circulation between the condenser 28 at this time and the evaporating means 34. The liquid refrigerant in the primary system evaporates within the evaporating portion 20 and is conducted

downwardly through conduit 138 to a conduit 140 which is in heat exchange relation with the conduit 40 and thus the refrigerant vapor in the conduit 140 absorbs the heat of liquid from the liquid refrigerant flowing through the conduit 40 by counterflow heat transfer.

This conduit 140 connects to the liquid trap 142 at the bottom of the condenser 144. This refrigerant vapor then flows upwardly through the condenser 144, while the weak liquor flows from the conduit 66 into the container 146 and thence downwardly through the condenser 144 to meet the upward flowing refrigerant vapor. In this way, the weak liquor is cooled in the upper portion of the condenser and in the lower portion absorbs the ascending refrigerant vapor in a counter-flow absorption arrangement so that this weak liquor now becomes fully enriched and collects in the liquid trap 142 from which it is drained through the drain conduit 152 which connects to the lower portion of the reservoir portion 150 of the other generator. In this way, the second generator is gradually filled with fully enriched liquor during the heating of the other generator.

It should be noted that the weak liquor from the generator being heated is taken from the front end of the jacket surrounding the heating flue 56 at which the temperature is the highest and the liquor is the weakest. This hot weak liquor thence flows through the conduit 60 to the lower end of the outer jacket of the heat interchanger 54 and exchanges its heat by counter-flow heat transfer with the rich liquor which flows from the bottom of the reservoir portion 50 through the inside of the heat exchanger 54 to the lower portion of the rear end of the jacket surrounding the heating flue 56. This cools the weak liquor considerably and the weak liquor is further cooled in the conduit 62, the restrictor 64 and the conduit 66 before it reaches the container 146 at the top of the second condenser 144.

The restrictor 64 controls the flow of weak liquor from the jacket surrounding the heating flue 56 in accordance with the pressure differential existing between the different portions of the system and, likewise, the refrigerant flows through the restrictor 24 in accordance with the pressure differential existing between the different portions of the system. Thus, the flow of refrigerant from the generating side to the absorption side is controlled by the same factors which control the flow of weak liquor from the generating side to the absorption side. In this way, by properly proportioning the restrictors 24, 64 and 164, the rate of flow of refrigerant and weak liquor may be correctly proportioned to insure the greatest efficiency.

The contents of the reservoir portion 50 is gradually reduced by the passing of the refrigerant vapor into the condenser 44 and by the passing of the weak liquor into the condenser 144 upon the absorption side of the system. When substantially all of the liquid is drained from the reservoir 50 and the liquid level in the jacket surrounding the heating flue 56 begins to fall, the temperature of a thermostat 76 mounted upon the top of the front portion of the jacket becomes sufficiently high to throw the swinging burner 68 from the full line position shown in Fig. 1 to the dotted line position. This is done by a mechanism generally designated by the reference character 78 and better shown in Figs. 2 and 3. This mechanism 78 is connected to a thermostat bulb 76 by capillary tubing 80 and is

also connected by capillary tubing 180 to a thermostat bulb 176 mounted upon the flue 156 of the generator which has been filling up with enriched liquor.

Thus, when the one generator 82 is substantially drained of liquor, the other generator 182 is substantially filled with rich liquor, the thermostats 76 and 176 thence cause the burner 68 to swing from the flue 56 to the flue 156 in order to reverse the system. This reversal causes refrigerant in vapor form to be separated from the liquor in the generator 182 and to pass upwardly through the conduit 148 to the container 146 and thence to be condensed in the condenser 44, after which it passes upwardly through the conduits 140, 138 and the primary evaporating portion 20 to the restrictor 24 which controls the flow of liquid refrigerant to the primary evaporating portion 22 where the liquid refrigerant evaporates and cools the container 28. The vapor from the secondary volatile liquid condenses in the container 28 to keep the evaporator 34 at the proper temperature.

The refrigerant evaporated in the evaporating portion 22 passes through the conduits 38 and 40 to the bottom of the condenser 44, while weak liquor from the generator 182 flows through the conduit 162 under the control of the restrictor 164 to the conduit 166 which conducts the weak liquor to the container 46 at the top of the condenser 44. This weak liquor is cooled in the top of the condenser 44 and meets and absorbs the evaporated refrigerant rising in the condenser and absorbs the refrigerant vapor in counter-flow fashion. This enriches the weak liquor and the enriched weak liquor then flows into and gradually fills the generator 82.

The liquid absorbent may be water, and the refrigerant may be ammonia or one of the sets of liquid absorbents and refrigerants mentioned in the Fleischer Patent No. 2,035,541 may be used.

The thermostatic throttling valve

The evaporating means 34 is kept at the proper temperature by a throttling valve 210 located in series with the gas supply conduit 212 which through the conduit 214 feeds the swinging Bunsen-type burner 68. This throttling valve opens in accordance with the temperatures of two thermostat bulbs. One of the bulbs 216 is located in heat exchange relation with the evaporating means 34 and the other 218 is located in heat exchange relation with the air in the compartment 36. These bulbs are each connected by capillary tubing 220 and 222 to the throttling valve 210.

The capillary tubing, the bulbs and the actuating portion of the throttling valve 210 are preferably charged with some suitable gas which will not condense at temperatures to which it is subjected, one example being carbon dioxide. The thermostat bulbs are preferably charged with some suitable adsorbent such as activated charcoal or activated silica. In such a system, the pressure of the gas is in accordance with the sum of the effect of the temperature conditions upon each of the bulbs 216 and 218. Thus, with this system, the valve tends to open wider under either a high evaporating temperature or a high compartment temperature and conversely, the valve tends to close under either a low evaporator temperature or low compartment temperature conditions.

Referring now more particularly to Fig. 4 for a detailed disclosure of the throttling valve 210, the

common capillary tube 224 connects at one end to the capillary tubes 220 and 222 and at the other end is connected to a threaded plug 226 which extends into the valve casing 228 and has a bellows 230 connected at its inner end. This plug 226 may be turned to move the bellows 230 inwardly or outwardly to adjust the position of the bellows. The threaded plug 226 is provided with a drilled aperture which at one end connects with the interior of the capillary tubing 224 and at the other end communicates with the interior of the bellows 230.

Within the bellows 230, there is provided a bellows stop 232 which cooperates with a head upon the valve stem 234 to prevent excessive expansion of the bellows 230. The one end of the bellows 230 is fastened to a bellows stop 232 and to the threaded plug 226, while the opposite end is connected to an end plug which is soldered to the valve stem 234. The valve stem 234 at its opposite end carries a valve 236 for closing the valve opening in the dividing wall 238. The dividing wall 238 is also provided with a small aperture 240 which allows a small amount of gas to flow from one side of the wall to the other, even when the valve 236 is closed, in order to prevent the gas burner from going out when the temperatures within the evaporating means and the compartment to be cooled are low. The valve body 228 is provided with an inlet connecting fitting 242 for connecting with the supply pipe 212 and is provided with an outlet fitting 244 for connection with the pipe 214 which, in turn, connects to the burner control 78.

The valve 236 also has riveted to it on the opposite side of the wall 238 a spring member 246. This spring member is tensioned by a cup-shaped member 248 which is riveted to a member 250. This member 250 is connected to a mushroom-shaped diaphragm seal 252 which makes a sealing connection to a bushing 254 in the closing plate 256. This closing plate 256 is fastened to the valve body 228 by the screws 258. Threaded into the bushing 254 is a threaded adjusting sleeve 260 having a knurled end portion 262. This adjusting sleeve 260 is held in place by a locking member 264 which is provided with a shoulder 266 which locks with a complementary shoulder upon the threaded bushing 254. The locking member 264 is also threaded onto the adjusting sleeve 260, but is normally locked to it by the clamping screw 268. Thus, this arrangement normally prevents the rotation of the adjusting sleeve 260. In order to adjust the sleeve 260, it is necessary to loosen the clamping screw 268 and to turn the sleeve 260 by employing the knurled end 262.

The adjusting sleeve 260 carries a bracket 270, which is provided with a spring latch in the form of a leaf spring 272 which has its end portion adapted to fit into the notch 274 in the rod 276 when it is desired to defrost the secondary evaporating means 34. This is done by pushing the head 278 of the rod 276 inwardly until the spring latch 272 engages the notch 274. This places the inner end of the rod 276 in engagement with the member 250, thus applying additional spring pressure onto the valve 236 tending to keep the valve in closed position. When the temperature of the evaporating means 34 becomes sufficiently high, there will be sufficient gas pressure in the bellows 230 to force the valve 236 to open position and to force the rod 276 outwardly by forcing the spring latch 272 out of the notch 274. The notch is provided with a cam surface

so that the spring latch 272 may be forced out of the notch by sufficient axial force upon the rod 216. The spring latch 272 may have its tension adjusted by the adjusting screw 280. The sleeve 260 provides an adjustment by which the temperature at which the valve is forced open may be adjusted. The temperature normally kept in the compartment 36 and in the evaporating means 34 is adjusted by adjusting the screw plug 226.

The swinging burner control

Referring now more particularly to Figs. 2 and 3, for the details of the burner controlling device, the housing 78 is provided with the plugs 184 and 84 which connect to the capillary tubing 180 and 80 which, in turn, connect to the thermostat bulbs 176 and 76. The plug 184 has the open end of the bellows 186 connected to it, while the plug 84 has the open end of the bellows 86 connected to it. The bellows 186 has its end closed by a plug 188, while the bellows 86 has its end closed by a plug 88. The plug 188 receives a conically pointed screw 190, while the plug 88 receives the conically pointed screw 90. These screws 90 and 190 are guided by a U-shaped bracket 302 and bear upon opposite sides of the web portion 304 of a primary lever 306 which is pivoted upon the pivot pin 308. This primary lever 306 carries the knife edge of a secondary lever 310 which has its opposite end connected to a tension toggle spring 312 which, in turn, is connected to an arm 314 extending from a bracket 316, also pivoted upon the pin 308. This bracket 316 in turn is connected to another bracket 318 which, in turn, connects to the burner tube 68.

This burner tube 68 is in the form of an elbow having its outlet 322 at its upper end and its inlet 324 at its lower horizontal end. This lower horizontal end is exactly in alignment with the pivot pin 308. This horizontal inlet portion 324 is provided with a venturi and mixing mouth 326, as is common for gas burners which is fed by the pipe 214 which extends from the throttling valve 210. This pipe 214 at the portion entering the venturi and mixing portion of the burner is in exact alignment with the pivot pin 308. Thus, no joint is required between this connecting portion of the pipe 214 and the burner 324. This burner 324 is generally of the Bunsen type and projects a flame into the heating flues 56 and 156.

As shown in Figs. 1, 2 and 3, the burner 68 is in position to heat the heating flue 56 and the generator 82. The double toggle snap acting device provided by the primary lever 306, the secondary lever 310 and the toggle spring 312 holds the burner tube 68 in this position until the thermostat 76 becomes sufficiently hot to overcome the force of the toggle mechanism. This occurs only when the generator 82 is substantially exhausted of refrigerant. At this time, the bellows 86 will contain gas at sufficient pressure to overcome the toggle mechanism and will expand to move the toggle mechanism across dead center, thus moving the burner tube 68 from the position at which it heats the flue 56 to the dotted line position in which it heats the flue 156. The top of the casing 78 is provided with set screws 330 and 332 for stopping the burner tube in each of its extreme positions.

While the form of embodiment of the invention as herein disclosed, constitutes a preferred form, it is to be understood that other forms might

be adopted, all coming within the scope of the claims which follow.

What is claimed is as follows:

1. Absorption refrigerating apparatus including evaporating means, a plurality of generating means, and a condensing means connected between each of said generating means and the evaporating means; means for alternately heating said generating means, said generating means being charged with a liquid absorbent, and means for transferring liquid absorbent from the generating means being heated to the generating means being cooled.

15 2. Absorption refrigerating apparatus including evaporating means, a plurality of generating means, and a condensing means connected between each of said generating means and the evaporating means; means for alternately heating said generating means, said generating means being charged with a liquid absorbent; means for conducting weak liquor from the generating means being heated to the condensing means connected to the second generating means for absorbing refrigerant from the evaporating means.

30 3. Absorption refrigerating apparatus including evaporating means, a plurality of generating means, and a condensing means connected between each of said generating means and the evaporating means; means for alternately heating said generating means, said generating means being charged with a liquid absorbent; means for conducting weak liquor from the generating means being heated to the condensing means connected to the second generating means for absorbing refrigerant from the evaporating means, and means for conducting the thus enriched weak liquor from said condensing means to said second generating means.

40 4. Absorption refrigerating apparatus including an evaporating means, a plurality of condensing means having their lower ends each connected to said evaporating means, a plurality of generating means containing a liquid absorbent, vapor conducting means connecting each of said generating means to the upper portion of one of the condensing means for supplying refrigerant in vapor form, liquid conducting means for connecting the lower end of each condensing means to its generating means, means for conducting weak liquor from each of said generating means to the upper portion of the condensing means connected to the other generating means, and means for alternately heating said generators.

55 5. Absorption refrigerating apparatus including evaporating means, a plurality of generating means, and a condensing means connected between each of said generating means and the evaporating means; means for alternately heating said generating means, said generating means being charged with a liquid absorbent, and means for transferring liquid absorbent from the generating means being heated to the generating means being cooled; said generating means including a reservoir portion, a heating portion, and a heat transfer portion between said reservoir portion and the heating portion, said heat transfer portion providing a heat exchange between the liquid absorbent and the refrigerant separated from the liquid absorbent.

60 6. Absorption refrigerating apparatus including evaporating means, a plurality of generating means, and a plurality of heat transfer means, means for alternately heating the generating means and condensing the refrigerant in one of

the heat transfer means, means for conducting weak liquor from the generating means being heated to another of said heat transfer means, and means for conducting evaporated refrigerant from said evaporating means to said another heat transfer means.

7. Absorption refrigerating apparatus comprising evaporating means divided into two portions by a throttling means, said two portions being substantially thermally isolated, a plurality of heat transfer units connected to the evaporating means, a plurality of generating means connected to said heat transfer units, means for alternately heating said generating means, a compartment to be cooled, a single common secondary volatile liquid system for cooling said compartment including a cooling unit in heat exchange relation with said compartment, said cooling unit containing a volatile liquid, said single common secondary system having a portion located above the level of liquid in the secondary system extending into heat exchange relation with both portions of said evaporating means.

8. Absorption refrigerating apparatus comprising two parts, each including means for generating, absorbing, and condensing refrigerant, evaporating means connected between the means of said two parts, said parts containing liquid absorbent and refrigerant, means for conducting liquid absorbent from one part to another, said conducting means including restrictor means for regulating the flow of liquid absorbent.

9. Absorption refrigerating apparatus comprising two parts, each including means for generating, absorbing, and condensing refrigerant, evaporating means connected between the means of said two parts, said parts containing liquid absorbent and refrigerant, means for conducting liquid absorbent from one part to another, said conducting means including restrictor means for regulating the flow of liquid absorbent, and restrictor means for regulating the flow of refrigerant from one part to another.

10. Absorption refrigerating apparatus comprising two parts, each including means for generating, absorbing, and condensing refrigerant, evaporating means connected between the means of said two parts, said parts containing liquid absorbent and refrigerant, means for conducting liquid absorbent from one part to another, said conducting means including separate restrictor

means for regulating the flow of liquid absorbent in opposite directions.

11. Absorption refrigerating apparatus comprising two parts, each including means for generating, absorbing, condensing, and evaporating refrigerant; said parts containing liquid absorbent and refrigerant, means for conducting liquid absorbent from one part to another, said conducting means including restrictor means for regulating the flow of liquid absorbent, and restrictor means for conducting refrigerant between the two parts.

12. Absorption refrigerating apparatus comprising two parts, each including generating and absorber-condenser means, evaporating means connected between the means of said two parts, said parts containing liquid absorbent and refrigerant, means for conducting liquid absorbent from one part to another, said conducting means including restrictor means for regulating the flow of liquid absorbent.

13. Absorption refrigerating apparatus comprising two parts, each including generating and absorber-condenser means, evaporating means connected between the means of said two parts, said parts containing liquid absorbent and refrigerant, means for conducting liquid absorbent from one part to another, said conducting means including restrictor means for regulating the flow of liquid absorbent, and restrictor means for regulating the flow of refrigerant from one part to another.

14. Absorption refrigerating apparatus comprising two parts, each including generating and absorber-condenser means, evaporating means connected between the means of said two parts, said parts containing liquid absorbent and refrigerant, means for conducting liquid absorbent from one part to another, said conducting means including separate restrictor means for regulating the flow of liquid absorbent in opposite directions.

15. Absorption refrigerating apparatus comprising two parts, each including generator, absorber-condenser means, and evaporating means; said parts containing liquid absorbent and refrigerant, means for conducting liquid absorbent from one part to another, said conducting means including restrictor means for regulating the flow of liquid absorbent, and restrictor means for conducting refrigerant between the two parts.

DON E. DASHER.
